UNITED STATES PATENT OFFICE.

THOMAS BRADY, OF EAST ORANGE, NEW JERSEY, ASSIGNOR TO BRADY ELEVATOR EQUIPMENT COMPANY, INC., OF HOBOKEN, NEW JERSEY, A CORPORATION OF DELAWARE.

DOOR-CLOSURE MECHANISM.

Application filed May 2, 1923. Serial No. 636,047.

To all whom it may concern:

Be it known that I, THOMAS BRADY, a citizen of the United States, and a resident of East Orange, county of Essex, and State of New Jersey, have invented certain new and useful Improvements in Door-Closure Mechanism, of which the following is a specification.

This invention relates to door closures for elevator hatchways.

It is very essential that the closure mechanism for elevator hatchway doors be so constructed and arranged that the door can not be opened from the floor landings.

When lever mechanism or other latching mechanism is used the door is not latched unless it is entirely closed and therefore if the door is left partly opened it can be opened from the floor level.

To overcome this condition rack and pawl mechanism has been used to prevent the door being opened until it has been entirely closed. This arrangement, however, has been objectionable because of the noisy operation of the rack and pawl.

This invention has for its salient object to provide rack and pawl door control mechanism so constructed and arranged that it will operate noiselessly.

Another object of the invention is to provide mechanism of the character described that will operate effectively and can be economically manufactured.

Further objects of the invention will appear from the following description taken in connection with the drawings which form a part of this application and in which,

Fig. 1 is an elevational view illustrating a three panel door, lever closure means and rack and pawl controlling means for the door.

Fig. 2 is a top plan view of the construction shown in Fig. 1, illustrating particularly the lever closure mechanism.

Fig. 3 is an elevational view on an enlarged scale showing the rack and pawl mechanism illustrated in Fig. 1, these parts being shown in the position taken when the door has not been entirely closed.

Fig. 4 is a sectional elevation taken at right angles to Fig. 3.

Fig. 5 illustrates the position of the parts

when an attempt has been made to open the door when it has not been entirely closed. 55

Fig. 6 is an elevational view showing the rack and pawl mechanism mounted at the bottom of a door panel and illustrating a slightly different construction of rack and pawl mechanism. 60

Fig. 7 is a sectional elevation taken at right angles to Fig. 6.

Fig. 8 is a top plan view of the rack shown in Figs. 6 and 7, and

Fig. 9 is a top plan view of the rack 65 shown in Figs. 1-5.

The invention briefly described consists of a rack and pawl, one of these members being mounted on the door or on a slidable door section and the other member being 70 mounted on a stationary support in the hatchway. The pawl is provided with a slot adjacent the toothed end thereof and in the slot is mounted a pin upon which are mounted rollers. When the door is opened 75 the rollers will hold the pawl tooth in elevated position so that it will not engage the rack and this action will also take place when the door is closed. However, if the door is not entirely closed but is nearly 80 closed the pawl will be positioned as shown in Fig. 3 and any attempt to open the door from this position will cause the pawl tooth to engage the rack teeth. In the embodiment of the invention shown in Figs. 1-5 85 85 the pawl is pivoted on a stationary bracket and the rack is carried by the door section. In the embodiment shown in Figs. 6-8 inclusive, however, the pawl is mounted on the door section and the rack is mounted on a 90 stationary support.

In the embodiment of the invention illustrated in Figs. 1-5 and 9 a three-panel door is illustrated, the panels being indicated at 10, 11 and 12. In this arrangement the section 12 is stationary and the sections 10 and 11 are slidable. 95

Any desired form of operating means may be used but in the embodiment of the invention illustrated this operating means comprises a plurality of links A, B and C. The link A is pivoted at 13 to the door section 10 and the link B is pivoted at 14 to the link A. The link B is also pivoted at 15 to a bracket 16 secured to the section 11. The link B and the link C are pivotally connected at 17 and 100 105

the opposite end of the link C is pivoted at 18 to a lug 19 secured in the elevator hatchway. In the particular form of the invention illustrated in Fig. 1 a dash pot or cushion 20 is pivoted at 21 to an extension 22 formed on the link C in order to secure a quiet operation of the door operating mechanism. A handle 23 is shown as secured to the link B.

In order to open the door the operator 10 pulls downwardly on the handle 23 and the link B swinging the parts to the position shown in dotted lines wherein the sections 10 and 11 have been moved to a position overlapping the stationary section or panel 15 12. It will be understood that any other form of door operating means may be utilized if desired.

In the form of the invention shown in Figs. 1-5 inclusive and 9, the rack 28 is 20 mounted on the section 10 adjacent the upper edge thereof and the pawl 29 is pivoted at 30 on a plate 31 secured above the hatchway opening. It will be seen from the showing in Fig. 1 that the pawl is located in such 25 a position that it will swing freely on its pivot when the door is entirely closed or when the door is entirely opened.

The pawl 29 has formed therein adjacent the toothed end 32 thereof an elongated slot 33 in which is mounted a pin 34 having mounted thereon rollers 35. In this form of the invention the rack has a pair of rails or tracks 36 on which the rollers are adapted to run and the rack teeth 37 are formed intermediate these rails. The tracks or rails 36 are flared at their ends as shown at 36^a to 35 guide the pawl into position above the rack. The under side of the rack is recessed as shown at 38 and openings 39 are provided at 40 the bases of the teeth to permit dust and dirt to pass downwardly into the recess 38 from which this matter can be cleaned out. The rack is secured to a bracket 40 in a position slightly offset from the panel 10.

45 The door is shown in Fig. 1 in full lines in its fully closed position. When the door is opened the pawl 39 will be swung in an anti-clockwise direction and the rollers 35 will ride on the tracks 36 retaining the toothed end 32 of the pawl out of engagement with the rack teeth thereby providing a noiseless operation. When the door is closed the pawl will be swung in a clockwise direction and the rollers 35 will again ride on the tracks 50 36. If, however, the door is not entirely closed but is stopped in a position such as is 55 illustrated in Figs. 3 and 5 and the operator or some unauthorized person tries to open the door the pin 34 will ride upwardly in the slot 33 permitting the toothed end 32 of the pawl to engage one of the rack teeth. In 60 order to open the door therefore it will be necessary to entirely close it permitting the pawl to swing downwardly to the position 65 shown in Fig. 1.

The construction shown in Figs. 6, 7 and 8 is similar to that shown in the preceding figures. In this construction, however, the pawl 51 is pivoted at 52 on a plate 53 secured to the bottom of the door panel 54. 70 The rack 55 is mounted below the hatchway opening and is provided with two sets of rack teeth 56 and 57. At the ends of the track 62 the rack base is recessed and flared as shown at 62^a to guide the roller 61 into proper position on the track. This construction operates as follows. When the door is opened the roller will ride on the track 62 thereby elevating the pawl above the rack. When, however, the door is closed in the direction 75 shown by the arrow in Fig. 6 the pawl will swing to the position shown in full lines and if the door is stopped in the position shown in this figure and an attempt is then made to open it, the pawl teeth will engage the rack 80 teeth.

Although certain specific embodiments of the invention have been particularly shown and described, it will be understood that the invention is capable of further modification 90 and that further changes in the construction and in the arrangement of the various cooperating parts may be made without departing from the spirit or scope of the invention as expressed in the following claims. 95

What I claim is:—

1. Pawl and rack mechanism comprising relatively slidable members, a rack mounted on one of said members, a pawl pivoted on the other member, said rack and pawl being constructed and arranged to prevent relative movement of said members in one direction when the pawl engages the rack teeth, and means carried by the pawl for elevating the pawl above and out of engagement 100 with the rack teeth when one of said members is moving relative to the other member, said means permitting the pawl to engage the teeth when the members are so relatively moved as to move the pawl into such engagement. 105

2. Pawl and rack mechanism comprising relatively slidable members, a rack mounted on one of said members, a pawl pivoted on the other member, said rack and pawl 115 being constructed and arranged to prevent relative movement of said members in one direction when the pawl engages the rack teeth, and means including a roller carried by the pawl for elevating the pawl above the rack teeth when one of said members is moving relative to the other member, said means permitting the pawl to engage the teeth when the members are so relatively moved as to move the pawl into such engagement. 120

3. Pawl and rack mechanism comprising relatively slidable members, a rack mounted on one of said members, a pawl pivoted on the other member, said rack and pawl being 125

- constructed and arranged to prevent relative movement of said members in one direction when the pawl engages the rack teeth, and means including rollers carried by
- 5 the pawl for elevating the pawl above the rack teeth when one of said members is moving relative to the other member, said means permitting the pawl to engage the teeth when the members are so relatively moved
- 10 as to move the pawl into such engagement.
4. Pawl and rack mechanism comprising relatively slideable members, a rack mounted on one of said members, a pawl pivoted on the other member, said rack and pawl being
- 15 constructed and arranged to prevent relative movement of said members in one direction when the pawl engages the rack teeth, and means including rollers carried by the pawl and movable bodily relative thereto,
- 20 for elevating the pawl above the rack teeth when one of said members is moving relative to the other member, said means permitting the pawl to engage the teeth when the members are so relatively moved as to
- 25 move the pawl into such engagement.
5. Pawl and rack mechanism comprising relatively slideable members, a rack mounted on one of said members, a pawl pivoted on the other member, said pawl having a longitudinal slot therein, a pin loosely mounted in said slot and rollers mounted on said pin.
6. Pawl and rack mechanism comprising relatively slideable members, a rack mounted on one of said members, a pawl pivoted on
- 30 the other member, and a roller carried by said pawl and movable bodily relative thereto and longitudinally thereon.
7. Pawl and rack mechanism comprising relatively slideable members, a rack mounted
- 35 on one of said members, a pawl pivoted on the other member, and rollers carrier by said pawl and movable bodily relative thereto and longitudinally thereon.
8. In combination, a rack having teeth
- 40 formed thereon and having a track disposed
- parallel to said teeth and a pawl having a tooth adapted to engage the rack teeth and a roller slidably mounted thereon and adapted to roll on said track.
9. In combination, a rack having teeth
- 50 formed thereon and having a track disposed adjacent to said teeth and a pawl having a tooth adapted to engage the rack teeth and a roller slidably mounted thereon and adapted to roll on said track.
10. In combination, a rack having teeth
- 55 formed thereon and having a track disposed adjacent to said teeth and a pawl having a tooth adapted to engage the rack teeth and a roller slidably mounted thereon and adapted to roll on said track, and means for retaining the roller on the track.
11. In combination, a rack having teeth
- 60 formed thereon and having a track disposed adjacent to said teeth and a pawl having a tooth adapted to engage the rack teeth and a roller slidably mounted thereon and adapted to roll on said track, and means for guiding the roller to and retaining the
- 65 roller on the track.
12. In combination, a rack having teeth
- 70 formed thereon and having tracks disposed adjacent to said teeth and a pawl having a tooth adapted to engage the rack teeth and rollers slidably mounted thereon and adapted to roll on said tracks.
13. Pawl and rack mechanism comprising relatively slideable members, a rack mounted on one of said members, a pawl pivoted on the other member, said rack and pawl being
- 75 constructed and arranged to prevent relative movement of the members in one direction when the pawl engages the rack teeth and means for elevating the pawl above and out of engagement with the rack teeth when
- 80 relative movement of the members takes place in the opposite direction.
- In witness whereof, I have hereunto set my hand this 30th day of April, 1923.
- THOMAS BRADY.
